YORK

APPARATUS FOR THOROUGHLY INTERMINGLING GASES OR VAPORS WITH MOLTEN
SUBSTANCES

Application filed February 17, 1931, Serial No. 516,469, and in Germany March 18, 1930.

This invention relates to apparatus for thoroughly intermingling gases or vapors with molten substances, particularly with molten metals or alloys.

5 It is necessary in many cases, to bring substances in vapor phase into contact with molten substances, for example with molten metals or alloys, so as to purify same by removing certain constituents. As an example may be mentioned the refining of lead from zinc by means of chlorine gas. This has hitherto been carried out by introducing the gases under pressure directly into the molten bath, or by pumping the molten metal through 10 a vessel which contains the gas. The devices of the last-named type for introducing gas into molten baths suffer from the drawback that an excessive expenditure of power is necessary for carrying out the pumping operation. Moreover the known processes as a 15 whole suffer from the drawback that the gases and the melt do not come into such intimate contact as is required for attaining the object of the process. For these reasons the known 20 processes take a very long time before the operation is completed, which entails a large consumption of fuel and an excessive expenditure of labour.

The present invention relates to apparatus 25 for thoroughly intermingling gases or vapors with molten substances and particularly with molten metals or alloys, according to which the aforesaid drawbacks are obviated. The apparatus consists of a centrifugal pump which is suspended in the molten bath and the suction pipe of which is so constructed that the gas to be employed for the reaction between the gas and metal gains access to the pump simultaneously with the 30 molten metal or the molten alloy.

In order more clearly to understand the 35 nature of the invention, reference is made to the accompanying drawing, which illustrates diagrammatically and by way of example, 40 one embodiment of the apparatus suitable for

carrying out the invention and the working thereof.

In said drawing, 1 depicts a vessel which is filled with molten metal. 2 is a centrifugal pump dipping into the molten metal bath, 50 said pump being driven by an electric motor 3. The pump and motor are mounted upon a frame 4, constructed of wrought iron. The whole apparatus consisting of pump, motor and the frame can be raised and removed 55 from the bath by means of lifting tackle. The depth of immersion of the pump in the molten metal bath can be adjusted as desired by means of a suitable device, and in the present case, by means of adjusting screws 5 which are situated at the ends of the frame 4. A suction pipe 6 with a suction port 7 for the molten metal is provided underneath the pump. The gas delivery pipe 8 also debouches simultaneously into the suction pipe 6. 9 is the delivery pipe for the centrifugal pump and 10 is the delivery port. 60 65 70

The apparatus operates in the following manner:

When the pump is started, it sucks up the 75 molten metal through the suction pipe and simultaneously reduces the pressure in said suction pipe, the result being that gas coming from any source in the direction indicated by the arrow, obtains access to the suction pipe and enters the pump body in conjunction with the molten metal. By increasing or diminishing the size of the suction port 7 by means of a throttling flange 11, the pressure therein 80 can be reduced to any desired extent. The mixture of gas and metal entering into the pump body 2 is intermingled to an extremely thorough extent on account of the rotation of the vane wheel of the pump, so that the particles of metal and the gas are brought into 85 mutual contact in a very fine state of subdivision. A rapid reaction therefore occurs between the components by virtue of this thorough intermingling and the reaction product is then delivered into the metal bath to 90

gether with the molten metal through the delivery pipe 9, and may either separate out on the surface of said metal bath, or when it is in a gaseous state, will escape therefrom.

- 5 Obviously, instead of producing an artificial vacuum in the suction pipe 6, the apparatus can also work by delivering the gas to the suction pipe under pressure. When the reaction between the metal and the gas in the 10 interior of the pump body or the delivery pipe 9 is also intended to take place under elevated pressure, this can be effected in various ways. Thus for example, it may be effected by attaching a throttling flange 12 to 15 the delivery port and by suitably increasing the speed of rotation of the vane wheel of the pump or by employing a multistage pump or alternatively, by employing all these measures in conjunction.
- 20 The apparatus of the present invention possesses the essential advantage that the entire reaction between the gas and metal takes place underneath the surface of the molten metal and therefore cannot be affected by the 25 atmosphere. Another characteristics feature is that the components are brought into extremely intimate contact and are very finely subdivided, the result of which is that a more rapid and intensive reaction between the gas 30 and metal takes place than was possible with the devices hitherto employed. The present apparatus thus enables the process to be shortened and a considerable saving in fuel and labour to be obtained also. In addition, 35 the present apparatus has the advantage over the known apparatus in that an exceedingly small consumption of power is required since the metal is only agitated within the metal bath, that is to say, no difference in 40 pressure has to be overcome.

In many cases, it may also be of advantage not to allow the reaction products to return directly into the same metal bath, but to convey them to another place of use, for example, to another vessel or into another molten metal bath or the like. This can also obviously be effected in the most simple way by suitably shifting the delivery pipe, no increase in the consumption of power being occasioned thereby. It is to be understood that the present invention is also applicable in a similar way to the intermingling of gases or vapors with liquid substances in general, apart from molten substances.

45 I claim:—

1. Apparatus for contacting a substance in vapor phase with a molten substance which comprises a centrifugal pump connected to a driving means, the pump body being provided with a suction opening for introducing the molten substance, an inlet for the substance in vapor phase, and an outlet for the contacted substances.

50 2. Apparatus as defined in claim 1 including means for effecting contact of the sub-

stance in vapor phase with the molten substance under elevated pressure.

3. Apparatus as defined in claim 1 including means for suspending said pump in a bath of the molten substance so that the pump body, together with the suction opening, the inlet for the substance in vapor phase and the outlet are positioned beneath the surface of the molten substance.

55 In testimony whereof I affix my signature.

PAUL WEFELSCHEID.
